(57) **CLAIM**

The ornamental design for an extraction tool, as shown and described.

DESCRIPTION

FIG. 1 is a front side perspective view of an extraction tool showing a first embodiment of my new design;

FIG. 2 is a rear side perspective view of the extraction tool of FIG. 1;

FIG. 3 is a rear view of the extraction tool of FIG. 1;

FIG. 4 is a front view of the extraction tool of FIG. 1;

FIG. 5 is a first side view of the extraction tool of FIG. 1;

FIG. 6 is a second side view of the extraction tool of FIG. 1;

FIG. 7 is a third side view of the extraction tool of FIG. 1;

FIG. 8 is a fourth side view of the extraction tool of FIG. 1;

FIG. 9 is a front side perspective view of an extraction tool showing a second embodiment of my new design;

FIG. 10 is a rear side perspective view of the extraction tool of FIG. 9;

FIG. 11 is a rear view of the extraction tool of FIG. 9;

FIG. 12 is a front view of the extraction tool of FIG. 9;

FIG. 13 is a first side view of the extraction tool of FIG. 9;

FIG. 14 is a second side view of the extraction tool of FIG. 9;

FIG. 15 is a third side view of the extraction tool of FIG. 9, and,

FIG. 16 is a fourth side view of the extraction tool of FIG. 9.

The broken lines depict portions of an extraction tool in which the design is embodied that are not considered part of the claimed design.

1 Claim, 9 Drawing Sheets
